[57] **CLAIM**

The ornamental design for a gas dispenser prop, as shown and described.

DESCRIPTION

FIG. 1 is a front elevational view of a gas dispenser prop, showing our new design;

FIG. 2 is a rear elevational view thereof;

FIG. 3 is a front, side, top perspective view of the gas dispenser prop; and,

FIG. 4 is a front, side, top perspective view of a second embodiment of the design shown in FIGS. 1-3.

The undisclosed opposite side and bottom views are planar and unornamented.
